UNITED STATES PATENT OFFICE.

PATRICK HENRY GINN, OF MIDDLETON, GEORGIA.

RAIL-JOINT SUPPORT.

No. 920,128.

Specification of Letters Patent.

Patented May 4, 1909.

Application filed June 14, 1907, Serial No. 378,984. Renewed March 26, 1909. Serial No. 486,025.

To all whom it may concern:

Be it known that I, PATRICK HENRY GINN, a citizen of the United States, residing at Middleton, in the county of Elbert and State of Georgia, have invented new and useful Improvements in Rail-Joint Supports, of which the following is a specification.

This invention relates to railroad rail joint supports for securely connecting rails together to support the joint thereof between a pair of ties and to also secure the rails on such ties so that they cannot spread and cause the derailment of a train, and the said invention consists in the construction, combination and arrangement of devices hereinafter described and claimed.

The object of my invention is to provide a novel form of device of this character, which may be manufactured at small cost and which is exceedingly strong and durable, acts efficiently to brace and support the meeting ends of rails at a joint and also serves to strengthen the construction of the ties on which the same is in use.

In the accompanying drawing,—Figure 1 is a top plan view of a railway joint provided with devices embodying my invention.

Fig. 2 is a side elevation of a railway tie provided with rail securing and supporting devices embodying my invention, the rails being shown in cross-section. Fig. 3 is a detail sectional view on a larger scale, on the plane indicated by the line 3—3 of Fig. 1.

In accordance with my invention I provide base plates or bars 1, which may be made of steel, iron or other suitable material and are of such size and shape as to enable the same to nearly cover a wooden railway tie *a* of ordinary construction. The rails *b* bear on such base plates or bars. On the upper side of said base plates or bars, near the ends thereof, are rail securing plates 2 which are secured thereon by spikes, bolts or other suitable devices, indicated at 3, which pass through registering openings in such plates and enter the tie. Such plates 2 are provided with inwardly extending arms 4 which are partly upturned to lie at a suitable angle and which bear on and embrace the base

flanges of the rails, as shown, so as to effectually secure the rail on the base plate of the tie and prevent the rail from spreading or moving laterally under the stress of a passing train.

Where my improved rail securing and supporting devices are employed at a joint between a pair of rails I form the plates 2 in pairs connected by an intermediate portion 4 bent in the form shown in Fig. 3 to provide, in addition to the portions 5 which bear on the upper sides of the rail base flanges, reversely turned arms 6 to bear under the bases of the rails and upturned arms or wings 7 to bear against the shanks of the rails between the bases and the heads thereof. The length of the connected pair of plates 2 is such as to enable them to lie on and bridge the space between a pair of ties at the rail joint and to extend for a suitable distance from opposite sides of the joint between the rails so that the connecting portions of the said pair of plates serve to support the ends of the rails and to form rigid braces therefor which prevent the ends of the rails from being depressed by the weight of passing trains. The vertical rings or arms 7 of the connecting portions of the plates 2 are secured to the rails by bolts or other suitable devices 8 which pass through alining openings in such rails and such vertical arms or wings.

The base plates 1 may be secured on the ties by any suitable means and in any suitable manner, within the scope of my invention.

For the purposes of this specification I have shown such base plates having their ends and central portions secured on the ties by means of railway spikes 9 of the usual form.

Having thus described the invention, what is claimed as new, is:—

The combination with ties having metallic base plates upon their upper sides, and rails disposed upon the base plates, of twin plates having their end portions disposed upon the plates and portions bent inwardly and upwardly to bear on the base flanges and against the sides of the shanks of the rails

between the heads and the base flanges thereof, said twin plates having portions intermediate their end portions reversely bent to bear under the bases of the rails and at 5 their ends on the base plates, said reversely bent portions and the said base plates being coextensive in thickness so that they lie in a common plane, and fastening devices en-

gaged with the end portions of the twin plates, the base plates and with the ties. 10

In testimony whereof, I affix my signature in presence of two witnesses.

PATRICK HENRY GINN.
